CLOTHESPIN

Harry L. Ratchford, Muncie, Ind.

Application October 18, 1949, Serial No. 5,552

Term of patent 14 years

(Cl. D17—6)

To all whom it may concern:

Be it known that I, Harry L. Ratchford, a citizen of the United States, residing at Muncie, Delaware County, State of Indiana, have invented a new, original, and ornamental Design for a Clothespin, of which the following is a specification, reference being had to the accompanying drawing, forming a part hereof.

The figure is a perspective view of a clothespin showing my new design. The sides opposite to the sides shown are identical thereto.

I claim:

The ornamental design for a clothespin, substantially as shown.

HARRY L. RATCHFORD.
